AUTOMOBILE FLOOR MAT

Ben Ross Jackler, Beverly Hills, Calif., assignor to Custom
Crown Mat Company, Inc., a corporation of California

Application September 24, 1954, Serial No. 32,424

Term of patent 14 years

(Cl. D9—6)

177048

MAR 6 1956

Fig. 1 is a front plan view of an automobile floor mat showing my new design;

Fig. 2 is a fragmentary inverted plan view thereof;

Fig. 3 is a fragmentary sectional view thereof taken on the line 3—3 of Fig. 1;

Fig. 4 is a fragmentary sectional view of the same taken on the line 4—4 of Fig. 1;

Fig. 5 is a composite fragmentary plan view of the upper longitudinal marginal portion of the mat, on a larger scale than Fig. 1;

Fig. 6 is a fragmentary inverted plan view of the upper left corner portion of the mat;

Fig. 7 is a fragmentary sectional view taken on the line 7—7 of Fig. 5;

Fig. 8 is a fragmentary sectional view taken on the line 8—8 of Fig. 5;

Fig. 9 is a fragmentary sectional view taken on the line 9—9 of Fig. 5; and

Fig. 10 is a fragmentary plan view of medallion portion of the central area of the mat, on a larger scale than Fig. 1.

I claim:

The ornamental design for an automobile floor mat, as shown.
